(57) **CLAIM**

The ornamental design for an elevated adjustable pet feeder, as shown and described.

DESCRIPTION

FIG. 1 is a perspective view of an elevated adjustable pet feeder showing my new design;

FIG. 2 is another perspective view thereof, but shown in an alternate configuration for clarity of illustration;

FIG. 3 is another perspective view thereof, but shown in another alternate configuration for clarity of illustration;

FIG. 4 is a front elevation view of FIG. 1;

FIG. 5 is a rear elevation view thereof;

FIG. 6 is a left side elevation view thereof;

FIG. 7 is a right side elevation view thereof;

FIG. 8 is a top plan view thereof; and,

FIG. 9 is a bottom plan view thereof.

The broken lines illustrate portions of the elevated adjustable pet feeder that form no part of the claimed design.
